UNITED STATES PATENT OFFICE.

FRANK DITCHFIELD, OF MONTREAL, QUEBEC, CANADA, ASSIGNOR TO AMERICAN STEEL FOUNDRIES, OF CHICAGO, ILLINOIS, A CORPORATION OF NEW JERSEY.

BRAKE-BEAM FULCRUM.

Application filed April 20, 1920. Serial No. 375,378.

To all whom it may concern:

Be it known that I, FRANK DITCHFIELD, a subject of the King of Great Britain, and resident of the city of Montreal, in the Province of Quebec and Dominion of Canada, have invented certain new and useful Improvements in Brake-Beam Fulcrums, of which the following is a full, clear, and exact description.

This invention relates to improvements in brake beam fulcrums and the object of the invention is to provide a cast fulcrum of simple and efficient design which may be adjusted to permit attachment of the brake lever with either right or left inclinations.

A further object is to provide a fulcrum which is solid between the compression and tension members of the brake beam and, therefore, has no tendency to work loose and permit improper movement in the beam.

Various attempts have been made to produce a universal fulcrum, that is to say, a fulcrum which may be adjusted to permit inclination of the brake lever to either right hand or left hand, but for the most part, such attempts have met with only partial success. At the present time, the majority of brake beam fulcrums are of solid one-piece-construction and are made right-handed and left-handed to give brake lever inclination in the desired direction. As these fulcrums are made up permanently in brake beams and cannot be changed without tearing the whole beam to pieces, it frequently happens that a railroad repair shop will be called upon to replace a greater number of left hand beams than right hand or vice versa, with the result that it soon becomes out of stock in beams of one hand and over-stocked with beams of the other hand. This condition necessitates carrying in stock a much greater number of beams than will be used.

An adjustable fulcrum has been produced and put into use which comprises a pair of end members connected to the beam and a revolute lever engaging portion connected between them. This device gives the desired adjustment and is very satisfactory when first put into operation. In a short time, however, movement between the parts commences which increases rapidly and soon renders the beam unsafe and unserviceable.

According to the present invention, a strut is provided having a continuous rigid

body between the compression and tension members of a brake beam and containing a revolute lever engaging member.

In the drawings which illustrate the invention;

Fig. 1 is a plan view of the fulcrum partly in section on the line 1—1, Figure 2.

Fig. 2 is a side elevation partly in section on the line 2—2, Figure 1.

Fig. 3 is a section on the line 3—3, Figure 1.

Fig. 4 is a view similar to Figure 3, showing the parts in operative position.

Fig. 5 is a fragmentary view similar to Figure 1, showing an alternative method of attaching the parts together.

Fig. 6 is a section on the line 6—6, Figure 5.

Referring more particularly to the drawings, 11 designates the body of a fulcrum and 12 a lever carrier or bearing mounted therein. The body comprises a pair of side plates 13 apertured at 14 and provided toward their ends with transverse webs 15, between which the member 12 is secured. The plates 13 are connected at one end by a suitably ribbed and stiffened part 16 adapted for engagement with the compression member of a brake beam, the design shown in the drawings being adapted for use with a brake beam having a channel compression member. The plates are connected at the opposite end by portion 17 adapted for engagement with the tension member of a brake beam. The side plates 13 are opened adjacent the head end 16, as at 18, to provide for the insertion and heading of a rivet 19 connecting the member 12 to the web 15. At the foot end 17, an aperture 20 is provided for the same purpose.

The member 12 is cylindrical in form and provided with a diametrically disposed slot 21 extending substantially from end to end. A pin 22 is provided traversing the slot 21 at a point intermediate the ends of the member, this pin being a sliding fit in the member and slightly smaller than the apertures 14 of the body, so that it may be inserted through these apertures into the member 12. The slot 21 is of sufficient length to permit of necessary movement of a brake lever connected to the fulcrum by the pin 22.

In practice, the brake lever lies at an angle of about 40° to the vertical and, to permit this positioning, the edges of the body 11 on

each side of the member 12 are flared at an angle of approximately 40° to the plane of the line 2—2, as shown at 23.

In Figures 5 and 6, a slight modification 5 is shown. The member 12^a is secured to the body 11^a by transverse bolts 24 instead of by the rivets 19. In each end of the member 12, two bolt holes 25 are provided arranged at an angle of approximately 80°, as clearly 10 shown in Figure 6.

The operation of the device is extremely simple. The fulcrum as shown in Figures 1 and 2 is made up as a normally inseparable part of a brake beam. When the beam 15 is to be placed on a car, it is supported in position in the usual manner and the member 12 disposed with its pin aperture in line with the body apertures 14. A brake lever is passed through the slot 21 and occupies 20 a vertical position. The pin 22 is inserted and the brake lever inclined to right or left of its vertical position as required. This movement of the brake lever rocks the body 12 about its axis and carries the pin 25 22 out of alignment with the apertures 14, as clearly shown in Figure 4, so that the pin is held by the body 11 against escape. When inserting a member 12 formed according to the modification shown in Figures 5 and 6, the bolts 24 are omitted until 30 the brake lever has been suitably inclined and are then inserted through whichever of the apertures 25 in the member 12^a align with the bolt apertures of the body.

35 From the foregoing description, it will be seen that a brake beam containing a fulcrum according to the present invention may be adjusted for either a right hand or a left hand inclination of a brake lever. The 40 body 11 is a one-piece, continuous strut between the compression and tension members of a brake beam and does not give any opportunity for working or movement between

the members of the brake beam. The member 12 to which the brake lever connects 45 has a large abutting surface on the webs 15 of the body, so that there will be no wear or loosening with continued use. The body 11 is in tension between the outer or foot end web 15 and the compression member and in 50 compression between this web and the tension member. As the body is in tension through the greater part of its length, it is 55 obviously not subject to collapse or buckling. The pin 22 cannot fall out and cannot be removed without disconnecting a large part of the brake mechanism. It will be clearly seen that the rivets 19 or bolts 24 do not serve as load transmitting members but are merely for the purpose of holding the parts 60 11 and 12 in proper relation, the load being transmitted directly from the part 12 to the part 11.

Having thus described my invention, what I claim is:—

1. A brake beam fulcrum comprising a body member continuous from end to end and adapted at one end to encircle the compression member of a brake beam and at the other end for co-operation with the tension 70 member of a brake beam, and a lever bearing revoluble in said body and integral abutments in said body engaging the entire end surfaces of said bearing.

2. A brake beam fulcrum comprising a body member, a reversible lever bearing mounted to turn therein and means for holding said bearing in either of two positions comprising intersecting bolt passages formed in the bearing and bolts adapted to 80 be inserted through said passages and the body member to hold the bearing against turning movement.

In witness whereof, I have hereunto set my hand.

FRANK DITCHFIELD.
